SAFETY RAZOR

Harry Swan, New York, N. Y., assignor to Patents
Incorporated, Wilmington, Del., a corporation
of Delaware

Application October 17, 1930, Serial No. 489,264

10 Claims. (Cl. 30—72)

My invention relates to safety razors and more particularly to safety razors of the double edge type.

The nature, objects, and advantages of my invention will become apparent from consideration of the following specification taken in conjunction with the accompanying drawings forming part of the specification and on which:

Fig. 1 is a top view of a razor constituting a first embodiment of the invention;

Fig. 2 is an end view of the same razor;

Fig. 3 is a sectional view taken on the line 3—3 of Fig. 1;

Fig. 4 is in part a longitudinal sectional view and in part a side elevational view taken on the line 4—4 of Fig. 1;

Fig. 5 is a bottom view of the razor;

Fig. 6 is a bottom view of blade and cap of the razor;

Fig. 7 is a view of the blade;

Fig. 8 is a bottom view of part of the guard of the razor and the blade;

Fig. 9 is an end view of the parts shown in Fig. 8; and

Figs. 10 to 18 are corresponding views of a second embodiment of the invention.

My razor shown in Figs. 1—9 includes a blade 10, a cap 12, and a guard 14. The blade is clamped between the cap and the guard by means of a stud 15 projecting inwardly from the cap and a handle 16 having an internally threaded bore adapted to screw onto the stud 15 to draw the cap and guard together. The razor is generally symmetrical about its longitudinal center line and also about its transverse center line. These center lines are indicated at A—A and B—B, respectively, in Fig. 5.

The guard member comprises a bearing part 18 which contacts the blade in operative position along longitudinal fulcrum edges 19 which are shorter than the total length of guard and shorter than the total length of the blade. At the ends of the fulcrum edges 19 are guard lips or corner projections 20, one at each corner. The guard lips project outwardly as shown in Fig. 2 in such manner that the blade in clamped position would rest on the guard lips were it not for cut-away corners in the blade, which will presently be explained.

The bearing part of the guard has a central aperture 21 through which the stud 15 passes and projections 22 adjacent aperture 21 for determining the position of the bearing part of the guard with respect to a wheel carrier part 25 of the guard. The bearing part is recessed centrally

at the ends with rectangular recesses 26 which receive cap projections 27. Just inside the recesses 26 are projections 29 having reduced portions 30 fitting snugly into apertures 31 in the wheel carrier. The undercut portions of the projections 29 bear against the wheel carrier and the reduced portions 30 prevent relative transverse or longitudinal movement of the parts of the guard member. It will be clear that the guard parts 18 and 25 may be secured together to form 10 a single piece.

The wheel carrier has a flat central portion apertured at 31 and in the middle to receive the projections 30 and stud 15, respectively. The handle 16 bears against the underside of the 15 wheel carrier adjacent the central aperture as shown in Fig. 4 and the clamping of the parts pulls them together. There is only one relation of positions between the bearing part 18 and the wheel carrier 25, the two parts acting as one 20 member, although there may be a variety of positions between the cap, the blade and the guard.

At the edges of the wheel carrier are rows of guard wheels 34. Each guard wheel is mounted on a spindle and the spindles are journaled in 25 struts 35. The struts may be formed by punching a series of holes in the carrier plate, slitting the outside edges of the holes and twisting the resulting projections obliquely with respect to the longitudinal center line and the plane of the 30 carrier and then bending them somewhat sideways. The arrangement is such that the wheels are oblique both to a plane normal to the carrier longitudinally and to a plane normal to the carrier transversely. The obliqueness is in opposite 35 relation on the two sides. Each strut, except the end struts, carries a spindle of one guard wheel at an inward point on one side of the plane of the carrier plate and a spindle of an adjacent guard wheel at an outward point on the other side of the plane of the carrier. The purpose 40 of this arrangement is to provide proper positioning of the blade relative to the guard wheels when the parts are in clamped position and to provide a smooth moving razor on the surface 45 to be treated. With the ordinary razor the hand provides the moving force and also regulates the direction of movement of the razor. With my razor, the hand merely supplies the force and the wheels determine the direction of movement. 50

A diagonal stroke is obtained, the direction being opposite for the two sides.

The cap 10 is transversely curved and has side edges farther from the longitudinal center line than the fulcrum edges 19 of the guard. When 55

the cap is screwed down on the blade, the blade, being of thin flexible steel is curved transversely, the blade being bent between the side edges of the cap and the fulcrum edges of the guard. The 5 cap is provided with end projections 27 which extend into the recesses 26 of the guard.

- The blade 10 is shown in Fig. 7. The blade is fixed in position along its center line. It has a central hole 37 through which stud 15 passes.
- 10 Holes 38 may be provided or not, as desired. Slots 39 are cut into the ends of the blade. These slots are of rectangular shape to correspond to the rectangular shape of projections 27 which fit into these slots. It will be seen that the blade is symmetrically reduced on the center line and that the ends of the center line portion are at right angles to the center line, which helps to prevent distortion or warping of the blade when the blade is bent in the holder.
- 15 The blade is shorter at the lateral edges than the more inward portions. The overall length is indicated at O in Fig. 7. The length of the lateral portions is indicated at L in Fig. 7. The width of the lateral portions is indicated at W in Fig. 7.
- 20 It will be seen that the shorter lengths L and the widths W provide what may be termed cut-away corners at the four corners of the blade. Each corner has one side at right angles to the longitudinal center line of the blade and a side parallel to the longitudinal center line of the blade.
- 25 The lateral portions consequently have ends at right angles to the longitudinal center line. This is important in preventing warping of the blade on being curved transversely. As can be seen in Fig. 8 the lateral portion extends outwardly from the fulcrum edge 19. That is, the ends are at right angles to the longitudinal center line from the outer edges inwardly to or substantially to the fulcrum edges. Consequently the line of contact between the blade and the fulcrum edge is of 30 the same length and parallel to the line of contact of the cap and the blade. This provides uniform bending and prevents the warping stresses which occur in a blade having curved ends.
- 35 The cut-away corners are in juxtaposition to the guard lips 20. The guard lips extend into the cut-away corners so as to be in alignment with the lateral portions of the blade and guard the ends of the cutting edges. The arrangement is such that if the corners were not cut away the blade 40 would contact the guard lips on urging the parts of the razor together and the guard lips would cause distortion of the blade. The guard lips effectively screen the corners of the blade without 45 obstructing its use during shaving.

The embodiment shown in Figs. 11 through 18, inclusive, differs somewhat from the embodiment of the previously described figures. In the second embodiment the cap is of greater extent at the 50 outside edges with respect to the extent of the cutting portion of the blade, so that the corners of the cap are in juxtaposition to the cut-away corners of the blade in addition to the juxtaposition of the guard lips 20 with the cut-away corners of the blade. Furthermore, the guard lips extend 55 upwardly beyond the blade in clamped position. That is, the guard lips 20 project farther into the cut-away corners of the blade than in the first embodiment. Thus, the corners of the blade are protected to a greater extent in this embodiment than in the first embodiment.

The blade of the second embodiment has a longitudinal slot 40 instead of the three holes 37, 38 of the first embodiment. The slot extends substantially the length of the razor, leaving rela-

tively narrow bridges at the ends of the center portion of the blade. The blade being fixed in position by the projections 27 of the cap, the opening along the center of the blade may be of any shape. The non-cutting end portions of the blade 5 may be curved off to prevent cutting the fingers in handling the blade.

It will be understood that the invention is not limited to the specific structure disclosed.

What I claim is:

1. A safety razor of the double edge type comprising a guard, a cap, a flexible blade and means for clamping the blade between the cap and the guard in curved position, the guard, the cap and the clamping means constituting a holder for the 15 blade, said blade being symmetrical with respect to a longitudinal center line and having cut-away corners providing lateral blade portions having ends at right angles to said center line and more centrally disposed portions extending longitudinally beyond the lateral portions, guard lips on the guard projecting into the cut-away corners when the parts are clamped together and means other than the guard lips and the cut-away corners for fixing the relative position of the guard, 20 the cap and the blade.

2. A safety razor of the double edge type comprising a guard, a cap, a flexible blade and means for clamping the blade between the cap and the guard in curved position, the guard, the cap and 30 the clamping means constituting a holder for the blade, said blade being symmetrical with respect to a longitudinal center line and having cut-away corners providing lateral blade portions having ends at right angles to said center line and more centrally disposed portions extending longitudinally beyond the lateral portions, said guard having fulcrum edges a given distance from the longitudinal center line, said cap having side edges further from the longitudinal center line than the 35 fulcrum edges, the blade being bent by the cap on the fulcrum edges as pivots, the ends of the lateral blade portions extending substantially between the side edges of the cap and the fulcrum edges and projections on one of the holder members in 40 juxtaposition to the cut-away corners.

3. A safety razor of the double edge type comprising a guard, a cap, a flexible blade and means for clamping the blade between the cap and the guard in curved position, the guard, the cap and 50 the clamping means constituting a holder for the blade, said blade being symmetrical with respect to a longitudinal center line and having cut-away corners providing lateral blade portions having ends at right angles to said center line and more centrally disposed portions extending longitudinally beyond the lateral portions, said guard having fulcrum edges a given distance from the longitudinal center line, said cap having side edges further from the longitudinal center line than the 55 fulcrum edges, the blade being bent by the cap on the fulcrum edges as pivots and the ends of the lateral blade portions extending substantially between the side edges of the cap and the fulcrum edges.

4. A safety razor comprising a flexible and elastic blade of oblong contour and internally apertured to receive positioning and clamping means, a guard member adapted to support the blade adjacent to the side edges of the latter, 70 a transversely-concaved blade-clamping cap provided with parallel side edges, means for positioning the blade between the cap and the guard member, and means for clamping said parts together and simultaneously causing the side edges 75

of the cap to flex the blade transversely on the guard member as a fulcrum, the blade being provided with unsharpened ends and with re-entrant recesses located at its corner portions respectively and each extending both longitudinally and transversely of the blade and cap to such an extent as to span the corresponding cap corner and provide a clearance space of sufficient area to receive said cap corner if bent toward the guard member, whereby a bent cap corner is prevented from exerting pressure on the blade while being flexed or when clamped and thereby breaking the blade or distorting its cutting edge.

5. A safety razor comprising a flexible and elastic blade of oblong contour and internally apertured to receive positioning and clamping means, a guard member adapted to support the blade adjacent to the side edges of the latter, a transversely-concaved blade-clamping cap provided with parallel side edges, each of the aforesaid parts being symmetrical about a longitudinal center line, the side edges of the cap being further apart than the side edges of the guard member, means for positioning the blade between the cap and the guard member, and means for clamping said parts together and simultaneously causing the side edges of the cap to flex the blade transversely on the side edges of the guard member as fulcrums, the blade being provided with unsharpened ends and with reentrant recesses located at its corner portions respectively and each extending both longitudinally and transversely of the blade and cap to such an extent as to span the corresponding cap corner and provide a clearance space of sufficient area to receive said cap corner if bent toward the guard member, whereby a bent cap corner is prevented from exerting pressure on the blade while being flexed or when clamped and thereby breaking the blade or distorting its cutting edge.

6. In a safety razor of the Gillette type having a holder including a guard, a cap and clamping means, said holder having blade positioning structure separate from the corners and being constructed to diminish blade exposure on tightening of the clamping means and said guard having fulcrum edges, an elastic transversely-flexible razor blade of substantially uniform thickness and so thin as to require external support on both sides thereof for substantially the full length of its cutting edge to give rigidity thereto, and being also provided with reentrant recesses located at its corner portions respectively and each extending both longitudinally and transversely of the blade to such an extent as to provide a clearance space for spanning the adjacent cap corner when the blade and cap are assembled, said corner reentrant recesses providing lateral blade portions, each being at least substantially as long at its cutting edge as at its base and being sufficiently wide to extend between the guard fulcrum and cap side edges of the razor.

7. In a safety razor of the Gillette type, a guard, a cap, a thin flexible blade and means for clamping the blade between the cap and guard in curved position, the guard, cap and the clamping means constituting a holder for the blade, said blade being symmetrical with respect to a longitudinal center line and having cut-away corners providing lateral portions and more centrally disposed portions extending longitudinally beyond the lateral portions, one of said holder

members having projections spanned by the cut-away blade corners with clearance, each lateral portion having a cutting edge at least as long as the length of the inward part thereof, said holder having means separate from said projections for positioning the blade in the holder and the holder being so constructed that tightening of the clamping means causes diminution of blade exposure.

8. In a safety razor of the double edge type, a guard, a cap, a thin flexible blade and means for clamping the blade between the cap and the guard in curved position, the guard, the cap and the clamping means constituting a holder for the blade, said guard having fulcrum edges a given distance from the longitudinal center line of the razor, said cap having edges further from the longitudinal center line than the fulcrum edges, said blade being formed to have lateral portions, each lateral portion having a base substantially at a fulcrum edge of the guard and extending outwardly to a cutting edge beyond the edge of the cap, the cutting edges being at least as long as said bases, and the blade having portions inwardly of the bases of greater length than the length of the bases, the parts being so constructed that on tightening the clamping means, the blade exposure is diminished.

9. In a safety razor of the double edge type, a guard, a cap, a thin flexible blade and means for clamping the blade between the cap and the guard in curved position, the guard, the cap and the clamping means constituting a holder for the blade, said guard having fulcrum edges at a given distance from the longitudinal center line of the razor, said cap having edges further from the longitudinal center line than the fulcrum edges, said blade being formed to have lateral portions, each lateral portion having a base substantially at a fulcrum edge of the guard and extending outwardly to a cutting edge beyond the edge of the cap, the cutting edges being at least as long as said bases, and the blade having a portion inwardly of the bases of greater length than the length of the bases, the parts being so constructed that on tightening the clamping means, the blade exposure is diminished, said holder having projections extending across the ends of said lateral portions and having means other than said projections for positioning the blade in the holder.

10. In a safety razor of the Gillette type having a holder including a guard, a cap and clamping means, said holder having blade positioning structure separate from the corners and being constructed to diminish blade exposure on tightening the clamping means, an elastic transversely flexible blade having edges arranged to engage said positioning structure to hold the blade against angular displacement and being of substantially uniform thickness and so thin as to require external support on both sides thereof for substantially its full length to give rigidity to its cutting edge, and being also provided with reentrant recesses located at its corner portions respectively and each extending both longitudinally and transversely of the blade to such an extent as to provide a clearance space for spanning the adjacent cap corner when the blade and cap are assembled, said blade having cutting edges at least as long as the distance between the inner corners of the reentrant recesses.

HARRY SWAN.
